UNITED STATES PATENT OFFICE

ELI ISRAEL, OF WILKES-BARRE, PENNSYLVANIA, ASSIGNOR OF ONE-HALF TO RALPH ISRAEL, OF WILKES-BARRE, PENNSYLVANIA

LAMP HOLDER FOR MINERS' CAPS

Application filed April 11, 1929. Serial No. 354,420.

This invention relates to lamp holders and more particularly to a lamp holder adapted to be secured to a miner's hat and by means of which a lamp may be supported 5 in front of the hat.

One object of the invention is to provide an improved lamp holder so formed that lamps of a conventional construction but provided with different types of attaching 10 members may be selectively applied to the lamp holder and each firmly connected therewith and prevented from moving out of its proper position in front of the hat above its brim.

Another object of the invention is to provide a lamp holder which may be formed from sheet metal and will be very strong and durable and prevented from being liable to be bent out of shape if roughly 15 handled.

Another object of the invention is to allow the lamp holder to be firmly secured against a support or mounting carried by the hat and prevent danger of the holder 20 being wrenched loose from its support when a lamp is applied to or removed from the holder.

Another object of the invention is to prevent danger of a miner being injured by 25 an electric shock if contact should be made with an overhead power wire while in a mine.

The invention is illustrated in the accompanying drawings, wherein

Figure 1 is a perspective view showing the improved lamp holder applied to a miner's hat,

Fig. 2 is a vertical sectional view through the hat and holder with an acetylene light 40 of a conventional construction applied to the holder.

Fig. 3 is a transverse sectional view taken on the line 3—3 of Fig. 2,

Fig. 4 is a perspective view looking at 45 the inner face of the holder,

Fig. 5 is a view similar to Fig. 2 showing an electric lamp of a conventional construction applied to the holder,

Fig. 6 is a transverse sectional view taken 50 on the line 6—6 of Fig. 5,

Fig. 7 is a view similar to Fig. 5 showing another conventional form of electric lamp applied to the holder, and

Fig. 8 is a transverse sectional view taken on the line 8—8 of Fig. 7.

The hat or cap shown in perspective in Fig. 1 and designated in general by the numeral 1 includes a crown 2 from which extends a forwardly projecting brim 3. A support 4 which is preferably formed of fiber is disposed vertically in front of the hat and has its lower portion bent forwardly to provide a foot 5 which rests upon the brim 3 where it is secured by suitable fasteners, such as the rivets 6. The upper portion of the support is bent to form a rearwardly extending tongue 7 which rests upon the top of the hat where it is secured by rivets 8 which pass through the hat, as shown in Figs. 2, 5 and 7, and are liable to

make contact with the head of a miner wearing the hat. A slot 9 extends transversely of the tongue 7 at approximately the front of the hat and from this slot extends a slot 10 which leads forwardly and extends downwardly through the upper portion of the support, as shown clearly in Fig. 2. In order to prevent danger of a miner receiving an electric shock from an overhead power wire, there has been provided a protecting sheet 11 formed of rubber or other suitable insulating material. This protecting sheet covers the rear portion of the tongue 7 and upper ends of the rivets 8 and is passed through the slot 9 so that it extends downwardly in front of the crown of the hat.

By this arrangement danger of an electric shock being conveyed to the head of a miner wearing the hat by way of the rivets will be eliminated.

The lamp holder, which is indicated in general by the numeral 12 and shown in perspective in Figs. 1 and 4, is preferably formed from sheet metal and is bent to provide a flange 13 which extends rearwardly from its upper end, the blank being crimped to form a lip 14 which extends downwardly intermediate the length of the flange. This lip consists of a double thickness, as shown in Fig. 3, and intermediate

its width the lip is bent, as shown at 15, to form a vertically extending passage constituting a socket open at its upper and lower ends. The front wall of the socket is formed with a slot 16 open at its upper end and merging into a slot 17 which extends forwardly through the flange and downwardly through the upper portion of the bracket, as clearly shown in Figs. 1 and 5. The intermediate portion 18 of the bracket is offset forwardly in order to provide a pocket 19 between the bracket and support 4 when the lamp holder is set in place and secured by the rivets 20 and this also causes the holder to be strengthened and prevented from being liable to be easily bent out of shape. Openings 21 are formed in the forward edge portion of the flange 13 adjacent opposite sides of the off-set portion 18 for communication with the pocket 19 and intermediate the depth of the offset portion there has been provided a transversely extending slot 22 beneath which the metal from which the lamp holder is formed is pressed forwardly, as shown at 23, to form an auxiliary pocket having its front wall extending downwardly at an inward incline and providing a cam surface.

When the improved lamp holder is in use, it is applied to the fiber support 4 and secured by the rivets 20 with the rear portion of the flange 13 overlying the strip of insulating material 11 which projects downwardly through the slot 9 in back of and beneath the lip 14. Since the lip fits snugly in the slot 9, it serves to prevent the holder or bracket from having sliding movement upon the support 4 and, therefore, the rivets 20 are relieved from strain exerted when applying a lamp to the holder or detaching a lamp. The carbide lamp 24 shown in Fig. 2 is of a conventional construction and this lamp carries a prong or hook 25 which extends rearwardly therefrom intermediate its width. When this type of lamp is applied to the holder, the prong is slid downwardly into the socket 15 until it is firmly seated and since a portion of the prong projects forwardly through the slot 16 and slot 17 the lamp will be prevented from having swinging movement transversely. By this arrangement the lamp can be very easily applied or removed and when in place it will be firmly anchored and prevented from moving out of its proper position. Since the strip of insulating material extends downwardly below the free end of the prong, it will be disposed between the prong and the crown of the hat and there will be no danger of the miner receiving an electric shock if the lamp should strike an overhead power wire and it has been previously explained that this strip of insulating material also prevents danger of a shock being received through the rivets 8.

In Fig. 5, there has been shown an electric clamp 26. This lamp is also of a conventional construction and is provided with an attaching tongue or strip 27 which extends rearwardly and then downwardly from the back of the lamp. The tongue 27 which is located approximately midway the width of the lamp is of sufficient width to be snugly received in the auxiliary pocket of the bracket, as shown in Fig. 6, and when it is passed inwardly through the slot 22 and forced downwardly the sloping outer wall 23 of this auxiliary socket exerts a cam action upon the tongue and causes a binding action to take place which will cause the tongue to be firmly held in the auxiliary pocket and prevent the lamp from accidentally becoming detached from his bracket.

In Fig. 7, there has been shown an electric lamp 28 which is also of a conventional construction and is provided at its rear with an attaching member 29 terminating in depending prongs 30. These prongs are spaced transversely from each other a sufficient distance to be received in the openings 21 so that they may be passed through these openings and into the pocket 19. When the prongs are engaged in the pocket, they fit snugly in opposite side portions thereof, as shown in Fig. 8, and a binding action will take place between the support 4 and forwardly projected portion 18 of the bracket and thereby prevent these prongs from moving upwardly and allowing the lamp to be accidentally released from the holder.

I have, therefore, provided a lamp holder which may be easily applied to a miner's cap and is so constructed that lamps of various conventional forms may be applied thereto and firmly but removably carried thereby. While it is stated that the bracket 12 is formed of sheet metal bent to assume the desired shape, it will be understood that it could be formed in other ways.

Having thus described the invention, I claim:

1. A lamp supporting attachment for caps comprising a bracket having a flange extending rearwardly from its upper end, a depending lip being provided intermediate the length of said flange and formed with a vertical passage intermediate its width constituting a socket, a slot being provided leading from the socket through the flange and upper end of the bracket whereby a securing prong of a lamp may be engaged in the socket with the upper portion of the prong projecting forwardly through the slot and supporting the lamp in front of the bracket.

2. A lamp supporting attachment for caps comprising a bracket having a flange extending rearwardly from its upper end, a depending lip being provided intermediate

the length of said flange and adapted to be engaged through an opening formed in a support carried by a cap, said lip having a vertical socket formed therethrough and a slot being formed through the upper end of 5 the bracket and leading forwardly from the socket whereby a lamp supporting prong may be passed through the slot and engaged in the socket, said bracket being offset forwardly intermediate its width and the flange being formed with openings spaced from opposite sides of the slot back of the offset portion of the bracket through which supporting prongs of a lamp may be passed.

15 3. A lamp supporting attachment for caps comprising a bracket having a flange extending rearwardly from its upper end, a depending lip being provided intermediate the length of said flange and adapted to be engaged through an opening formed in a support carried by a cap to brace the bracket, the said bracket being adapted to have a lamp removably engaged therewith.

4. A lamp supporting attachment for caps 25 comprising a bracket having a flange extending rearwardly from its upper end, a depending lip being provided intermediate the length of said flange and adapted to be engaged through an opening formed in a support carried by a cap, said bracket having a portion offset forwardly intermediate its width to provide a pocket between the bracket and its support when the bracket is secured to the support, and said flange having 30 openings formed therein adjacent opposite sides of the offset portion through which supporting prongs of a lamp may be passed into the pocket.

5. A lamp supporting attachment for caps 40 comprising a bracket having a flange extending rearwardly from its upper end, a depending lip being provided intermediate the length of said flange and adapted to be engaged through an opening formed in a support carried by a cap, said bracket having a portion offset forwardly intermediate its width to provide a pocket between the bracket and its support when the bracket is secured to the support, a slot being formed 45 transversely of the offset portion intermediate the height of the bracket and the intermediate portion of the bracket below the slot being projected forwardly to provide a cam surface to have binding engagement 50 with a supporting prong of a lamp when the prong is thrust inwardly through the slot.

6. A hat, a support disposed vertically in front of said hat and having a rearwardly 60 extending tongue overlying the top of said hat, said support being firmly secured to the hat and the tongue having an opening formed therein in front of the hat, and a bracket extending vertically in front of said 65 support and having a rearwardly extending

flange overlying the tongue and provided with a lip extending downwardly through the opening in the tongue, said bracket being adapted to be engaged by a lamp and support the lamp in front of the hat.

7. A hat, a support disposed vertically in front of said hat and having a rearwardly extending tongue overlying the top of said hat and formed with an opening in front of the hat, fasteners for said tongue passed through the top of said hat, a sheet of insulating material covering the fasteners and extending downwardly through said opening in front of the hat, a bracket fitting against the front of said support and having a flange extending rearwardly across said tongue and secured in overlying relation to the rear portion of the sheet of insulation, and a lip extending downwardly through the opening in said tongue with the strip of insulation disposed between the lip and front of the hat, said bracket being adapted to have a lamp engaged therewith and support the lamp in front of the hat.

8. A hat, a support disposed vertically in front of said hat and having a rearwardly extending tongue overlying the top of said hat, said support being firmly secured to the hat and the tongue having an opening formed therein in front of the hat, and a bracket extending vertically in front of said support and having a rearwardly extending flange overlying the tongue and provided with a lip extending downwardly through the opening in the tongue, said bracket being offset forwardly intermediate its width to reinforce the bracket and provide space in front of the support, openings being formed in the bracket and communicating with the said space whereby supporting prongs may be passed inwardly through the openings and lamps removably supported in front of the bracket.

In testimony whereof I affix my signature.
